UNITED STATES PATENT OFFICE.

SIMON CLARY, OF CARNEGIE, PENNSYLVANIA.

TIE-PLATE.

No. 859,046.

Specification of Letters Patent.

Patented July 2, 1907.

Application filed December 11, 1906. Serial No. 347,295.

To all whom it may concern:

Be it known that I, SIMON CLARY, a citizen of the United States of America, residing at Carnegie, in the county of Allegheny and State of Pennsylvania, have 5 invented certain new and useful Improvements in Tie-Plates, of which the following is a specification, reference being had therein to the accompanying drawing.

This invention relates to tie plates, particularly designed for supporting rails upon ties.

10 The invention has for its object to provide a simple and inexpensive plate for protecting a wooden tie from being injured from the movement of a rail thereon.

Another object of this invention is to provide a tie plate wherein novel means is employed for preventing 15 lateral displacement of a plate upon a tie.

A further object of this invention is to provide a tie plate for rails having means for preventing the lateral displacement of a rail upon the plate.

A still further object of this invention is to provide 20 tie plates upon which rails are secured, the plates being constructed to prevent the creeping of a tie.

With these and other objects in view, which will more readily appear as the invention is better understood, the same consists in the novel construction, combination and arrangement of parts to be hereinafter 25 more fully described and then specifically pointed out in the appended claims.

Referring to the drawing forming part of this specification, like numerals of reference designate corresponding 30 parts throughout the several views, in which:

Figure 1 is a top plan of my improved tie plate, Fig. 2 is an edge view of the same illustrating a rail mounted thereon, Fig. 3 is a bottom plan of the plate.

To put my invention into practice, I construct my 35 improved tie plate of strong and durable metal, which can be rolled or otherwise treated to produce the plates, either singly or in strips, which may be afterwards cut and punched to provide the plates. The plates are substantially rectangular in plan and each plate is 40 formed with a rail-seat 1 having side ribs or shoulders 2 adapted to brace the longitudinal edges of the base flange 3 of a rail 4. The plate adjacent to each end thereof is provided with spike openings 5, one opening passing through each one of the ribs or shoulders 2, 45 whereby when the plate is secured to a tie (not shown) by a spike, the spike will not only hold the plate upon the tie, but will overlie the edges of the base flange 3 and retain the rail 4 upon the plate and prevent vertical displacement of the same. The bottom of the plate is

recessed, as at 6, and provided with a longitudinally disposed central V-shaped rib 7 adapted to engage in the upper surface of a wooden tie and prevent lateral displacement of the tie plate. The bottom of the plate directly beneath the vertical edges of the ribs or shoulders 2 is provided with longitudinally disposed V- 55 shaped ribs 8, the lower edges of said ribs being in a plane horizontal with the lower edge of the rib 7. These ribs are also adapted to engage in the upper surface of a tie and prevent the tie plate from creeping or twisting upon the tie. 60

My invention particularly resides in the depending gripping ribs also in providing the sides of the plate with the longitudinal ribs or shoulders 2, both of said ribs serving functionally to prevent the rail 4 from laterally moving upon the tie plate, which is not accomplished 65 by the use of one rib.

When a tie plate is used adjacent to each end of a tie and the V-shaped gripping ribs of the plate become embedded in the tie, it will be impossible for the tie to creep beneath the rails especially when the rails are 70 fastened to their ties.

My improved tie plate has numerous advantages over plates heretofore designed for the same purpose, those advantages being readily apparent to those skilled in the art. 75

I do not care to confine myself to the exact contour of the tie plate or to its size, and such changes in the details of construction, as are permissible by the appended claims, may be resorted to without departing from the spirit and scope of the invention. 80

What I claim and desire to secure by Letters Patent, is:—

A railway tie plate having a body of relatively equal thickness from edge to edge, a rib on the upper face of the plate adjacent each longitudinal edge having a vertical inner face, the said plate having spike-receiving openings, and having a central longitudinal groove in its underneath face, a longitudinally-disposed V-shaped rib on the underneath face disposed centrally of said groove, and a longitudinal V-shaped rib on the underneath face of the plate 90 near each longitudinal edge, said last named ribs disposed directly beneath the vertical face of the ribs on the upper face of the plate and having their lower edges on the same horizontal plane as the lower edge of the central V-shaped rib. 95

In testimony whereof I affix my signature in the presence of two witnesses.

SIMON CLARY.
